UNITED STATES PATENT OFFICE.

CELIA M. SMITH, OF ITHACA, NEW YORK.

DESIGN FOR A PATTERN FOR PRINTED FABRICS.

SPECIFICATION forming part of Design No. 22,178, dated January 31, 1893.

Application filed November 12, 1892. Serial No. 451,822. Term of patent 3½ years.

To all whom it may concern:

Be it known that I, CELIA M. SMITH, a citizen of the United States, residing at Ithaca, in the county of Tompkins and State of New York, have invented and produced a new and original Design for Printing Fabrics; and I do hereby declare the following to be a full, clear, and exact description of the same, reference being had to the accompanying drawings, forming a part thereof.

The design to be printed, painted or otherwise placed upon a fabric is represented in said drawings in which:

My design for a pattern for a printed fabric consists in the matter herein shown and described. The boy is shown with out-stretched arms 1 and with feet 2 spread apart and is represented as having on a close fitting cap and jacket, short trousers and top boots or leggins.

A cap band with jewel is represented at 3 and a jeweled belt at 4.

5 The lines 5, 6 and 7 denote respectively a jeweled neck band or collar and jeweled bands, and 8 denotes a fringe or band at the bottom of each trousers leg. The neck and waist bands ornamented with representations of jewels are approximately parallel while the 30 bands 6 and 7 are obliquely disposed between them meeting in median lines at front and rear. In front the bands 7 touch the belt and in the reverse they meet at angles at a point above the belt.

9 denotes slashes and filling in the coat sleeves.

The various garments and the hands, face, hair and other parts may have appropriate colors and the whole is designed to suitably 40 represent a Columbian sailor boy. The entire contour of the representation in each figure is surrounded by a broken line situated near and everywhere approximately parallel thereto.

What I claim is:

The design for a pattern for printed fabrics herein shown and described.

In testimony whereof I affix my signature in presence of two witnesses.

CELIA M. SMITH.
